UNITED STATES PATENT OFFICE.

ELMER H. LUPTON, OF BALTIMORE, MARYLAND, ASSIGNOR TO THE BARTGIS BROTHERS CO., OF BALTIMORE, MARYLAND, A CORPORATION OF MARYLAND.

FOLDING BOX.

Application filed August 23, 1927. Serial No. 214,968.

This invention relates to folding boxes, made of paper stock and suitable for containing suits, coats, etc. The purpose of the invention is to provide a box with attached 5 cover which can be quickly set up or knocked down, which will fold flat for shipment, and which will occupy small space on the counter while the goods are being packed in the boxes.

The box comprises top and bottom portions 10 which are made separately from similar blanks, the blank for the top or cover portion being slightly larger than the blank for the bottom portion of the box. Each blank comprises a substantially rectangular 15 body portion, creased parallel with its edges, to provide walls for the box part and creased diagonally at its corners so that the latter may fold against opposing walls, and also having flaps projecting from two of its opposite edges, adapted to fold over the adjacent 20 walls and corner pieces. These flaps, on the bottom portion of the box, are secured in their central portions to the adjacent walls, the ends of the flaps being free. A blank of this 25 general character and a box part made therefrom are illustrated in patent to Bachmann, No. 855,746, although in the patent referred to, the flaps are at the ends of an oblong box, where the extra thickness caused by the flaps 30 and corner pieces on both parts of the box is undesirable; whereas, in my oblong box I arrange the flaps on the side walls to strengthen the box longitudinally. The bottom portion of the box of my invention is made with the 35 flaps at both sides turned inwardly and secured to the side walls; whereas on the top or cover portion only one flap is turned inwardly and secured to the adjacent side walls and the other flap is creased so that it may 40 fold either inwardly or outwardly with respect to its side wall, and this flap is secured by stitching, or otherwise, to the base or bottom of the bottom part of the box, with the crease running parallel with the side of said 45 part. In this way, the two parts of the box are permanently secured together and the one part will fold flat against the other. In setting up the box, the bottom portion is first 50 set up by pulling both of its side flaps outwardly, and the top part is set up by pulling one side flap outwardly, after which the top part is swung over the bottom part to make the complete closed box.

In the accompanying drawing,
55 Fig. 1 is a plan view of a blank, suitable for

forming either the top or the bottom of a box; Fig. 2 is a perspective view of the box folded for shipment;

Fig. 3 is a section on the line 3—3 of Fig. 2.

Fig. 4 is a perspective view of the box with 60 the bottom part set up for filling, and the top part folded;

Fig. 5 is a similar view, with the top part set up and ready to be closed over the bottom part;

Fig. 6 is a transverse section through the closed box; and,

Fig. 7 is a perspective view of a corner of the box, showing the manner in which the corner pieces fold under the side flaps.

Referring to the drawing, the top and bottom portions of the box are each made from a blank of the form shown in Fig. 1, the blank for the top part of the box being, of course, slightly larger than the blank for the bottom part, since the former part fits over the latter. The blank comprises a substantially rectangular body portion *a* and side flaps *a'*. As shown, the blank has creases 1 extending across it parallel with its ends, and creases 2, 75 extending lengthwise parallel with its sides, and it is also creased longitudinally in line with the sides of the body portion, as shown at 3. The flaps *a'* may bend with respect to the body portion along the creases 3, and these 80 flaps end substantially at the creases 1. The corner portions 4 of the blank are diagonally creased, as indicated at 5. The parts 6 of the blank, between the creases 1 and the ends of the blank, constitute the end walls, and the 85 parts 7, between the creases 2 and 3, constitute the side walls of one part of the completed box. In making the bottom part *b* of the box from a blank, the end walls 6 are turned inwardly over the main part of the 90 blank, as shown in Fig. 2, and the flaps *a'* are turned inwardly over the side walls 7, and said flaps are secured to the side walls by suitable means, preferably by stitches or 95 staples 8. The flaps are secured only in their central portions, the ends of the flaps being free, so as to permit the corner pieces 4 to fold thereunder.

The part *c* of the box, which constitutes the top, has its end walls folded inwardly 105 and one side flap *a*² folded against the end wall 7^a in the same way that the corresponding parts are folded in the bottom part *b* of the box. The flap *a*³ of the top *c* is, however, secured to the bottom 1^a of the bottom part of 110

the box by suitable means, such as stitches 9. The crease 2^a, which divides the flap a³ from the adjacent side wall 7^b of the top portion of the box, constitutes a hinge joint which 5 lies parallel with the lower edge of one of the side walls of the bottom part of the box, as shown in Fig. 5, so that the top c may fold flat under the bottom b of the box, as shown in Figs. 2, 3 and 4. As shown in Fig. 5, one 10 fold 4^a of each corner piece on the top, adjacent the side wall 7^b, is secured to said side wall by a stitch or staple 10. This is not essential, but is desirable for the purpose of effecting automatic folding of the corner 15 pieces.

In practice, when it is desired to set up a box, the folded structure is laid with the top or cover part c upon a table or counter, and by pulling outwardly on the end walls 6 of 20 the part b, the corner pieces 4 fold partly, as indicated in Fig. 7. The side walls 7 are then raised and the free ends of the flaps thereon are swung over the corner pieces and the bottom part of the box is then set up, as 25 shown in Fig. 4, and the box may then be filled. The setting up of the bottom portion b of the box may be done very quickly, and if the top portion is left folded under the bottom portion, very little space will be required on the 30 counter or table while the box is being set up and filled. After the box has been filled, it is lifted and the top portion c is swung outwardly and its end walls 6 and the side wall 7^a are raised, as shown in Fig. 5, the flap on the 35 latter wall covering the adjacent corner pieces. The cover may then be swung over the bottom part of the box. In this movement, the cover bends along the hinge joint formed by the crease 2^a and the adjacent corner pieces automatically fold along their 40 diagonal lines. When the box is closed, the

top or cover part of the box extends completely over the bottom part and the side walls 7^a and 7^b of the former lie close to the side walls 7 of the latter. The sides of the box are thus 45 very much strengthened by the several thicknesses of material, which is an advantage, particularly in relatively long boxes, such as are used for holding coats, suits, etc.

To knock the box down, it is merely necessary to swing the cover outwardly, as shown in Fig. 5, and press the side walls of the parts outwardly, thus releasing the corner pieces from the flaps, and the end walls will 50 then fold inwardly.

What I claim is:

A folding box comprising top and bottom parts formed from similar blanks, each blank comprising a rectangular portion creased 60 parallel with its edges to form walls and creased to form flaps on two opposing walls, and the corners of said portion being creased diagonally to fold against said opposing walls, said flaps, on the bottom part of the box, being folded inwardly and secured at 65 their central portions to their adjacent walls, the end portions of the flaps being free, to permit the adjacent corner pieces to fold thereunder, one flap on the top part of the box being similarly folded and secured at its 70 central portion to its adjacent wall and the other flap on the top part of the box being secured to the bottom part of the box with the crease forming said latter flap extending along a lower edge of the bottom part and 75 forming a hinge joint permitting the top part to swing on said joint over or under the bottom part.

In testimony whereof I hereunto affix my signature.

ELMER H. LUPTON.
